Application November 5, 1935, Serial No. 48,271

18 Claims. (Cl. 197—127)

This invention relates to record strip feeding mechanisms provided for printing mechanisms employed in record controlled tabulating machines and the main object of the invention is to provide a record strip spacing mechanism capable of automatically advancing a record strip in predetermined amounts.

The invention is shown applied to a record controlled tabulating machine of the Hollerith type in which groups of classified records are adapted to control the operation of the machine. Each of said records is designated to represent a classification number and the value which is to be entered into an accumulator and printed by a suitable printing mechanism. Such machines are adapted to print each amount by the printing mechanism as well as the total derived from the accumulator and machines of this type have heretofore been equipped with record strip spacing devices to automatically space each printed item and the total.

It is desirable, however, to widely space to differentiate each group of related items and accompanying total from the next group of items and its accompanying total in order that the record strip may subsequently be severed into separate sheets making up a bill or at times it may be desirable to provide a suitable spacing between each group of items and totals to accommodate a head spacing, etc.

The improved record strip feeding mechanism disclosed herein is adapted to not only automatically space the record strip but is also provided with control mechanisms whereby the record strip may be fed the desired amount.

It is a further object of the invention to provide variable record strip feeding operations under control of one of the tabulating records controlling the machine.

In the illustrative embodiment, the first record of each group is perforated in a selected column and the position of the perforation is adapted to automatically cause the desired extent of record strip feeding operation.

A still further object of the invention is to provide a suitable electrical controlling mechanism under control of the perforated record to adjust the record strip spacing mechanism and preferably as an accompaniment to printing a total.

In carrying out the present invention, a selected column of the record card is perforated and when the correlated analyzing device determines the presence of a perforation a selected relay is rendered operative. A plurality of re-

lays is provided and each relay is adapted to select for operation a particular record strip spacing control magnet. A general operator, preferably operated electrically, is adapted to be operated a predetermined extent under control of each of the record strip spacing control magnets and the general operator is adapted to cause the predetermined rotation of the customary platen carrying the record strip.

A still further object of the present invention is to provide a brake, preferably of the electromagnetic type, for cushioning the movement of the general operator at its final movement thereby preventing an overthrow movement of the platen during the record strip feeding operation.

While the improved record strip spacing mechanism is shown in the present embodiment as being operated as an accompaniment to printing a total, it will be understood that such application is for illustrative purposes only. By suitable modifications, which are obvious to those skilled in the art, the improved feeding mechanism may also be employed in connection with spacing the record strip as an accompaniment to printing an item, or for other purposes.

Other applications of the present embodiment will also be obvious as the invention is understood by recourse to the present specification.

Other and relatively important objects will be apparent as the invention is understood by reference to the following description and accompanying drawings, in which:

Fig. 1 is a view in side elevation of one embodiment of the invention for accomplishing record strip feeding movements of various extents. This figure also shows a conventional mechanism for controlling the differential positioning of type bars to a platen.

Fig. 2 is a sectional view taken on the line 2—2 of Fig. 1;

Fig. 3 is a sectional view taken on the line 3—3 of Fig. 1;

Fig. 4 is a plan view of part of the improved mechanism illustrating particularly the magnetic brake and the platen rotating mechanism;

Fig. 5 is a detail view of a conventional form of platen operating mechanism for feeding the record strip when printing an item and also when printing a total;

Fig. 6 is a plan view illustrating the form of record card preferably employed in connection with the present invention to control varying record strip feeding operations;

Fig. 7 is an electrical wiring diagram for the

electrical instrumentalities employed in connection with the present invention.

The present invention is shown applied to a tabulating machine of the type fully shown and described in Patent 1,762,145. As explained in this patent a series of classified perforated records 10 of the form disclosed in Fig. 6 is fed through the machine to control the setting of printing devices and entering of values or items 10 in accumulators for summing the values represented on the records. As an incident to feeding a record and performing a tabulating operation a shaft 11 (Fig. 7) is operated for a single revolution. During the first machine operation, 15 or cycle, the perforated record 10 is fed past a series of control brushes 12 and during a subsequent machine cycle past the value or item entering control brushes 13. The feeding rollers for feeding records in a successive manner from 20 a supply stack to the brushes 12 and 13 are diagrammatically shown in Fig. 7 but are fully described and shown in the Patents No. 1,762,145 and No. 1,600,413.

The records 10 which carry perforations 25 representing the items to be printed and entered in the accumulators are previously sorted into groups so that the records of one classification are together and the groups are fed in sequence. After a group of records is tabulated and the 30 items are entered in the accumulator a total is taken from the accumulator and printed on the record strip bearing the printed items. These successive item printings require that the record strip be fed a step preferably before each printing 35 operation so as to prevent over-printing.

As more fully shown and described in the aforementioned patent and Patent No. 1,600,413 in the description of the printing mechanism the brushes 13 analyze the several columns of value 40 representing perforations and as each brush 13 locates a perforation it causes a printer control magnet 14 (Fig. 1) to be energized. As the successive index point positions pass the brush 13 a type carrying bar 15 is elevated synchronously 45 so as to present the type to a platen 16 which corresponds to the particular index point analyzed. If a perforation is located at this time magnet 14 is energized and the latter shifts a call rod to the right and rocks a latch member 50 17 which releases a stop pawl 18. The latter engages with an appropriate notch 19 of the type bar. When all the type bars 15 are differentially set the usual printing hammers 20 are released to thereby print on the record strip surrounding 55 the platen 16 the item represented on the record. Thereafter the printing bars 15 are returned to normal in readiness to be set during the next machine cycle under control of the successive card 10 passing the brushes 13.

60 The manner in which items are spaced on the record strip from each other is well-known and is fully shown and described in the Patent No. 1,762,145. This particular mechanism is also shown in Fig. 5 but is briefly described herein as 65 it forms no part of the present invention.

Numeral 305 represents a rock shaft corresponding to the similarly numbered shaft in the Patent No. 1,762,145. To the shaft 305 there is connected an arm 21 having at its upper end a pin 22. As the shaft 305 is rocked in a clockwise direction this pin contacts with a shoulder 23 on a member 24 rocking a unit comprising members 25, 26 since this unit is constructed and connected to member 24 as follows: Lever 25 is pivotally mounted at 27 and is pivotally connected

at 28 to lever 24. The lever 26 and the lever 24 are each adjustably connected at their left hand ends at points 26a and 24a respectively, to the part 24. Parts 24, 25 and 26 after being once adjusted always operate as a single unit, and as stated is operated by shaft 305.

A link 29 is connected to the lever 25 and at its other end is connected to pawl and ratchet device 30 of the usual type for turning the platen 16 a step before each item printing operation.

As more fully shown and described in the aforementioned Patents Nos. 1,600,413 and 1,762,145, the machine to which the present invention is applied has incorporated therewith a mechanism for automatically taking a total from 15 the accumulator when the group numbers of the records 10 change. As previously intimated the records are successively presented to certain analyzing brushes 12 and 13 in order to determine the similarity or dissimilarity of group 20 number designations. Upon a change in a group number tabulating operations from records stop and the machine automatically takes a total.

As more fully shown and described in the Patent No. 1,762,145, the machine upon taking a 25 total causes the operation of mechanism for again rocking the shaft 305 (Fig. 5) before a total is printed thereby separating the last printed item from the total printed on the record strip. Since this mechanism is fully shown and 30 described in Patent No. 1,762,145, it will not be described since it forms no part of the present invention.

It is desirable, however, to feed the record strip to an extent greater than that performed 35 in either item printing or total printing operations in order to give a wide space between the total printed and the next item to be printed under control of the first record containing the next group number designation. The improved 40 mechanism for performing this function will now be described in detail. The first record 10 of each new group is perforated in a selected column in order to cause and further control the extent of the record strip feeding operation 45 effected after a total is printed.

In Fig. 6, the record 10 representing the first card of a group, is shown by way of example perforated in the first column at the "9" index point position to cause a record strip feeding 50 operation of a certain extent. The machine is further equipped with a means for selecting record strip feeding operations of other extents and in the present embodiment this is effected by perforating column "1" at one of the "7", 55 "8" or "9" index point positions.

Referring now particularly to Fig. 7, it will be noted that the brush 12 which first analyzes the first record of each new group is adapted to contact with a contact block 31 through the perforation in column "1", said contact block being connected to the positive line side 32 through cam controlled contacts 33. These contacts are closed by a cam rotated by the shaft 11 and the contacts 33 are adapted to be closed during the time that 65 all of the index point positions of the record are being analyzed. Brush 12 is electrically connected to a segment 34 against which bears a brush 35 during the time the record is being analyzed. The brush 36 which is electrically connected 70 to the brush 35 is adapted to successively engage with contact points 37 as the card is being analyzed.

When the "9" index point position is analyzed, for example, the brush 36 will be slightly to the 75

right past the position shown in Fig. 7 to engage with the first contact point 37 and if it is assumed that the "9" index point position is perforated, the circuit will be extended by the commutator 5 from the positive line side to a pick-up magnet 38 of a relay. It is obvious that if the first column is perforated in either the "8" or "7" index point position, magnets 38 of other relays will be selected for energization due to the independent electrical wiring connections 39 between the contact points 37 and the magnets 38 of the relays. Cam controlled contacts 40 are adapted to be closed by a cam secured to the shaft 11 during the time the index point positions of the record 15 are being analyzed thereby extending the positive line side to relay contacts 41, one of which is closed by the selected magnet 38, thereby causing the energization of a relay holding magnet 42 of said relays.

20 The magnets 38 are also adapted to close related contacts 43 and said contacts are connected to the negative line side 44 through cam controlled contacts 45 which are adapted to be closed and are closed before the cam controlled contacts 40 open. 25 Each of the contacts 43 is connected by means of a suitable plug connection 46 to a related spacing control magnet 47 and a holding relay magnet 57. Subscripts *a*, *b* and *c* are used hereinafter to designate particular magnets 47 and associated devices. It will be obvious, therefore, that upon the 30 closure of contacts 43, the associated magnets 47 and 57 will be connected through the relay contacts 43 and cam controlled contacts 45 to the negative line side 44. Each of the spacing control magnets 47 and relay magnet 57 is connected to the positive line side through contacts 48 which are closed by a cam rotatable with shaft 11. Contacts 48 are adapted to be closed at the time contacts 45 are closed and contacts 48 remain closed at the end of the item entering operation for the 35 last record of the group. Contacts 40, however, open before the end of the machine operation in which the last record of a group is analyzed there- 40 by causing the holding magnet 42 to be deener- 45 gized and since at this time cam controlled contacts 33 are open, the selected relay will be inop- 45 erative and the associated contacts 41 and 43 opened.

50 Contacts 45 are also opened before the end of the machine operation. However, when the selected spacing control magnet 47 is energized the contacts 49 of its associated holding relay 57 are closed thereby connecting the selected spacing control magnet 47 and relay magnet 57 to the negative line side 44 by means of a wiring connection 50 connected to each of the contacts 49.

55 Summarizing, therefore, it will be obvious that when the last record of a group is analyzed by 60 brushes 13, under control of the brushes 12 analyzing the first record of the succeeding group one of the spacing control magnets 47 and related relay magnet will be energized during this machine operation. At the end of the same ma- 65 chine operation the associated relay comprising magnets 38 and 42 and contacts 41 and 43 will subsequently be rendered inoperative, thereby placing the electrical record strip feeding select- 70 ing mechanism in condition ready for the next re- lay setup operation.

70 At the end of the machine operation just referred to, cam controlled contacts 48 will be retained closed and the selected spacing control magnet 47 will be held energized by the holding contacts 49 of the related holding relay 57.

As fully shown and described in the aforesaid Patent 1,762,145, the tabulating motor thereupon stops and this causes the stoppage of the shaft 11 and the turning of another shaft is then effected for causing a total taking operation. 5 This shaft is designated herein and in the aforesaid Patent No. 1,762,145 by the reference numeral 315. Shaft 315 as shown in Fig. 7 is adapted to close contacts 51 after a total has been 10 printed from the accumulator. Closure of contacts 51 will cause the energization of a main operating magnet 52, the function of which will presently be described in detail.

15 As is best shown in Figs. 1 and 4, the platen 16 is attached to a shaft 53 and to the shaft 53 there is secured a ratchet wheel 54 with which a pawl 55 is adapted to engage. The pawl 55 is pivoted upon one arm of a double arm 56 loosely mounted upon the shaft 53. Pawl 55 is urged by the usual 20 spring to engage the teeth of the ratchet wheel 54 and after the double arm 56 has been turned in a clockwise direction to turn the ratchet wheel 54, it is returned to its normal position by means of a spring 57. Pivoted to the upper portion of the 25 double arm 56 is a link 58 connected to a circular rod of magnetic material. The latter passes through a hole in a bracket plate 60 and also at its right end projects for a slight distance within the central portion of the magnet 52. Obviously, 30 with the construction just described the rod 59 will be attracted by the magnet 52 and will be drawn to the right (Fig. 1). The rod 59 is provided with lateral cuts 61 and 62 thereby providing stop shoulders 63 and 64. One of the spacing control 35 magnets designated 47c is shown in Fig. 2 and from the construction disclosed in this figure it will be obvious that when the magnet 47 is energized it will draw towards each other a pair of iron cores 65 thereby rocking towards each other a 40 pair of levers 66 pivotally mounted at 67 in bracket plate 60 in a scissors-like fashion.

45 It will be recalled that upon the presentation of the first record 10 of a new group one of the spacing control magnets 47 will be energized and held energized after the total printing operation. Assuming that the magnet 47c, shown at the 45 extreme right in Fig. 1, is energized, it will be obvious that each of the associated pair of levers 66 will act as an abutment to the stop shoulder 64 when the rod 59 is moved to the right due to the energization of the magnet 52.

50 Referring now to Fig. 7, the cam controlled contacts 51 are adapted to be closed by the cam secured to the shaft 315 after a total printing 55 operation. Since at this time the magnet 47 is already energized it will be obvious that movement of the rod 59 to the right will cause a certain movement of the rod and by means of the pawl 55 and ratchet wheel 54 the platen 16 will be rotated to thereby feed the record strip a predetermined extent of operation after the total printing has been effected.

55 The record strip is fed the smallest amount when the magnet 47a is energized under control 60 of a perforation located in the first record 10 of the new group. The movement of the rod 59, in this case, will be limited by the coaction of the shoulder 63 of the rod 59 with the side of the levers 66 actuated by the magnet 47a. Magnet 47c will cause the record to be fed a slightly 65 greater extent than shoulder 64, in this, abutting the levers 66 actuated by the relay magnet 47c.

70 The maximum feeding movement that can be 70 imparted to the record strip is performed under 75

control of the spacing control magnet 47b. This magnet will actuate its related levers 66 and by coaction of said levers with the shoulder 63, the movement of the rod 59 will be limited.

- 5 Summarizing therefore it will be evident that upon the energization of one of the magnets 47a, 47b, or 47c and the subsequent energization of the operating magnet 52, the rod 59 will be given a certain movement causing the pawl 55 10 to rotate the ratchet wheel 54 and thereby turn the platen the desired extent of movement. This will cause the total last printed to be spaced from the item pertaining to the first record of the new group and the spacing will vary in accordance with the spacing control magnets 47a, 47b or 47c selected for energization.

While the above described mechanism is entirely operative, it is preferable to provide suitable devices for cushioning the movement of the rod 59 caused by the energization of the operating magnet 52. To this end the rod 59 at its right end carries a rod 68 carrying a bevelled element 69 adapted to cause the closure of contacts 70a, 70b or 70c. When the magnet 47a 20 is selected for energization, the short movement given to the operating rod 59 will cause the element 69 to close contacts 70a as the operating rod 59 approaches its limit of movement. Correspondingly when rod 59 is given a larger movement under control of magnet 47c, the contacts 70c will be closed towards the limit of movement of the rod 59. In the same manner, contacts 70b are closed when the rod 59 is given its greatest extent of movement under control 30 of magnet 57b.

As best shown in Fig. 7, one blade of each of the contacts 70a, 70b, 70c is connected by a wire 71 to the positive line side 32. The other blade of each of the sets of contacts 70a, 70b, 70c is individually connected by wires 72 to related relay contacts 73a, 73b and 73c. The particular relay contact closed is dependent upon which relay 57 is energized. Each of the contacts 73a, 73b and 73c are electrically connected to wires 74 which serve to tap portions of an electrical resistance 75 which is in series electrically with a magnet 76 of a magnetically operated brake. The magnet 76 is connected by a wire 77 to the negative line side 44.

50 From the electric connections just described it will be obvious that when the rod 59 is given its smallest movement, contact 73a will be closed and insert the greatest amount of resistance in series with the magnet 76 and correspondingly 55 when the operating rod 59 is given its greatest extent of movement contacts 73b will be closed to insert the least amount of electrical resistance in series with the magnet 76.

60 The preferred form of magnetic brake is disclosed in Fig. 4 wherein it will be seen that within an annular ring 78 of a stationary plate member 79, there is fitted the magnet coil 76. The magnet coil 76 also projects within an annular ring 80 of a ring 81 which is slidably keyed by a key 82 to the shaft 53. Obviously, when the magnet 76 is energized, it will attract the ring 81 during the final rotation of the platen 16, thereby functioning as a magnetic brake and slowing up the rotation of the platen.

70 Obviously, a higher voltage is supplied to the brake magnet 76 when the rod 59 is given its greatest extent of movement to give the maximum braking effort and the voltage is reduced 75 for the smaller amounts of movement of the rod

59. This, as previously intimated, is effected by selection of the desired amount of resistance given by the electrical resistance element 75.

After the magnet 52 is energized and the rod 59 is given the desired movement, contacts 51 (Fig. 7) are opened thereby permitting spring 57 to restore the operating rod 59 to its normal position.

At the next operation of the machine which comprises a tabulating operation under control 1 of the first record of the new group, the shaft 11 will now be rotated and during its initial operation it will open contacts 48 (Fig. 7) thereby causing the deenergization of the selected spacing control magnet 47, relay magnet 57 and the 1 opening of the related relay contacts 49 and 73. The parts are now in normal position in readiness for another record strip feeding operation selected under control of the first record of the next group. 20

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following 30 claims.

What is claimed is:

1. In a machine of the class described, the combination with a platen, of driving means therefor, a plurality of independently energized electro-magnets, means to select an electro-magnet for energization, and means controlled by said electro-magnets for causing an operation of said driving means to an extent dependent upon the electro-magnet energized. 35

2. In a machine of the class described, in combination, a feeding mechanism for a record strip, a plurality of electro-magnets, means for energizing a selected electro-magnet for creating a predetermined magnetic field, and means controlled by said electro-magnets for causing a variable movement of said feeding mechanism in accordance with the magnetic field created. 45

3. In a machine of the class described, in combination, a platen, means for causing an operation of said platen, means including a plurality of solenoids for controlling the extent of operation of said means, and means comprising individual elements each operated alone for energizing a selected solenoid to predetermine the extent of operation of said platen. 55

4. In a machine of the class described, in combination, a platen, a driving mechanism therefor, a member adapted to be given movements of variable extents to control the extent of operation of the driving means, a plurality of stop devices for stopping the movement of said member, a series of electro-magnets each adapted by its energization to operate its related stop device, means for selecting a desired electro-magnet for energization, and means for causing a movement of said member. 60

5. In a machine of the class described, the combination with a platen, of a general operator for driving said platen, a plurality of electro-magnets each energized for predetermining the extent of operation of the general operator, means for energizing a selected electro-magnet and means operable thereby for predetermining the extent of operation of the general operator, 70 75

and electrical means for causing an operation of the general operator.

6. In a record controlled machine, the combination with a platen, of means for effecting a variable operation of the platen, and means operable in response to a single perforation in a record for controlling the operation of the first named means and to cause an operation of the platen to an extent which is variable with the particular location of the single perforation.

7. In a record controlled machine, the combination with means for analyzing a record to determine the location of a perforation, of a platen, a driving means therefor, and a plurality of electro-magnetically controlled means selectively controlled by said analyzing means for controlling the operation of the platen driving means to cause the latter to be operated to an extent which is variable with the location of the perforation in said record.

8. In a machine of the class described controlled by records occurring in classified groups demarcated by a special perforated record, a platen, means for causing an operation of said platen, and means operable in accordance with the location of a perforation in each special record for determining the extent of operation of said platen and effecting an operation to an extent which is variable with the particular location of the single perforation.

9. In a record controlled machine, in combination, a platen, a plurality of electro-magnets, means for analyzing a record and for energizing an electro-magnet in accordance with which position in a column said record is perforated, and means controlled by the electro-magnets for causing an operation of the platen to an extent in accordance with the electro-magnet energized.

10. In a record controlled machine, controlling records bearing designations under control of which successively spaced items are printed on a record strip, said records occurring in classified groups, a platen carrying said record strip, means for causing a variable movement of said platen, and means controlled by a perforation in a record, one record occurring in each group, for determining the operation of said means to cause a movement of the platen to an extent which is variable with the location of the perforation in the record.

11. In a machine of the class described, in combination, a platen adapted to be line-spaced as successive items are printed under control of tabulating records, said records occurring in classified groups, means for operating said platen to a variable extent, means for analyzing a predetermined column of a tabulating record demarcating successive groups to determine the location of a single perforation in the column, and means for causing the operating means to operate said platen to an extent which is variable with the location of the perforation.

12. In a record controlled machine capable of item entering operations, said machine having a rotatably mounted platen adapted to be line-spaced as an incident to item entering operations, the combination of a plurality of independently energized electro-magnets, means controlled by a perforation in a record for causing a selected magnet to be energized, and means controlled by said electro-magnets for causing a supplemental rotation of the platen to an extent dependent

upon the electro-magnet selected for energization.

13. In a record controlled machine capable of item entering operations, and total taking operations adapted to occur upon the presentation of a record of a new group, said machine having a rotatably mounted platen adapted to be line-spaced as an incident to item operations, the combination of a plurality of independently energized electro-magnets, means controlled by a perforation in one of the records of each group for causing a selected electro-magnet to be energized, and means controlled by said electro-magnets for causing a supplemental rotation of the platen to an extent dependent upon the electro-magnet selected for energization.

14. In a machine of the class described, in combination, a platen, a driving means therefor, a plurality of similar elements each operated alone, means controlled by a perforated record for causing the operation of a selected element in one machine cycle, means for continuing the operativeness of the selected element for the subsequent machine cycle, and means for causing the operation of the driving means during the subsequent machine cycle, and to an extent dependent upon the element selected for operation.

15. In a machine of the class described, in combination, a platen, a driving means therefor, electrical means for predetermining the extent of movement given to said platen by said driving means, and means comprising an electro-magnetically operated braking mechanism for retarding the movement of said platen.

16. In a machine of the class described operable in cycles, in combination, a platen carrying a record strip, a driving means therefor, a plurality of electro-magnets, each for governing the extent of movement of said driving means, means for analyzing a perforated record and for causing the energization of a selected electro-magnet in one machine cycle, electrical means for holding the energization of the selected electro-magnet and for continuing its energization during a subsequent machine cycle, and means for causing an operation of the driving means during the subsequent machine cycle to an extent dependent upon the electro-magnet energized.

17. In a machine of the class described, in combination, a platen, means including a member adapted to be given variable movements to operate said platen variable extents, an electro-magnetic brake mechanism for said platen including an electro-magnet in an electrical circuit, an electrical resistance in said circuit, a series of contact devices electrically connected in said circuit to vary the resistance in said circuit, said contacts being arranged to be operated successively by said member, and means for selecting the contact device adapted to be rendered operative by said member.

18. In a machine of the class described, in combination, a platen, means for driving said platen variable extents, an electro-magnetic brake mechanism including an electro-magnet for retarding the movement of said platen, an electrical resistance in a circuit of said electro-magnet for controlling the retarding action, and means for varying the amount of electrical resistance in said circuit in accordance with the extent of operation given to said platen.

FRITZ DIDZUNS.
